CLAIM

The ornamental design for a lipstick organizer, as shown and described.

DESCRIPTION

FIG. 1 is a front/left/top perspective view of a lipstick organizer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear/left/top perspective view thereof; and,

FIG. 9 is a cross-section view along line 9 in FIG. 2 of the lipstick organizer.

1 Claim, 9 Drawing Sheets
